CLAIM

The ornamental design for a tail portion of an fishing lure tail, as shown and described.

DESCRIPTION

FIG. 1 is a perspective view of a first embodiment of a tail portion of an artificial fishing lure of the present invention, wherein the tail portion is combined with a non-claimed body portion.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top plan view of FIG. 1.

FIG. 7 is a bottom plan view of FIG. 1.

FIG. 8 shows a state of use of the tail portion of the artificial fishing lure of the present invention, wherein the tail portion is attached to a non-claimed body portion.

FIG. 9 is a perspective view of a second embodiment of the tail portion of the artificial fishing lure of the present invention.

FIG. 10 is a third embodiment perspective view of a third embodiment of the tail portion of the artificial fishing lure of the present invention, in such a state that the tail portion is not combined with the non-claimed body portion.

FIG. 11 is a front view of FIG. 10.

FIG. 12 is a rear view of FIG. 10.

FIG. 13 is a left side view of FIG. 10.

FIG. 14 is a right side view of FIG. 10.

FIG. 15 is a top plan view of FIG. 10; and,

FIG. 16 is a bottom plan view of FIG. 10.

The broken lines in the figures illustrate the non-claimed body portion of the artificial fishing lure and form no part of the claimed design.

1 Claim, 16 Drawing Sheets
